UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

THREAD-CUTTING TEMPLE FOR LOOMS.

1,366,034.

Specification of Letters Patent. Patented Jan. 18, 1921.

Application filed December 17, 1918. Serial No. 267,113.

To all whom it may concern:

Be it known that I, EDWARD S. STIMPSON, a citizen of the United States, residing at Hopedale, county of Worcester, State of Massachusetts, have invented an Improvement in Thread-Cutting Temples for Looms, of which the following description, in connection with the accompanying drawing, is a specification, like characters on the drawing representing like parts.

This invention relates to improvements in thread cutting temples for looms and the object of the invention is to provide a simple and improved means whereby the movable blade shall be forced into engagement with the fixed blade during the cutting stroke thereby to secure an effective shearing action upon the thread or filling end.

Another object of the invention is to provide a temple thread cutter in which the movable member including the body, heel and blade portions is formed as a single integral cast iron member with the portion forming the cutter blade chilled in the casting operation so as to permit it to take an edge.

These and other objects and features of the invention will appear more fully from the accompanying description and drawings and will be particularly pointed out in the claims.

In the drawings,

Figure 1 is an end elevation of a temple head and adjacent parts embodying a preferred form of the invention;

Fig. 2 is a vertical sectional view of the construction shown in Fig. 1 taken on the line 2-2 of Fig. 1;

Fig. 3 is a detail in horizontal cross section taken on the line 3-3, Fig. 2;

Fig. 4 is a vertical cross section of the cutter blades and spring plate taken transversely of Fig. 2 with the movable cutter blade depressed and retracted to show the diverging relation of the cutter blades.

The general construction and purpose of a temple and a temple thread cutter for looms is so well known to those familiar with the weaving art that it is unnecessary to set the same forth in anything more than a general way.

The construction herein illustrated except for those features involving the present invention is and may be similar to that illus-

trated and described in my prior patent, Re- 55 issue No. 14420 granted January 8, 1918.

In this construction the bar of the usual temple the forward end of which is shown at 4 has formed thereon and secured thereto the temple head comprising the pod 5, the cap 6 with the inclosed toothed roll 7 journaled on the studs 8 and the entire bar and head move forwardly when the lay strikes the depending heel 9.

The cutting mechanism of the temple 65 comprises a vertical stationary cutter member shown as a flat steel blade 10 mounted at one side of a vertical recess in the head of the temple and held in position by a set screw 11. The corner 12 of this blade forms 70 the cutting edge thereof.

The movable cutter has a rocking as well as a backward and forward movement in the usual vertical recess in the temple head. In this invention this movable cutter member is 75 a single integral cast iron casting. It comprises a body portion 13 of generally rectangular shape, a depending heel 14 and a cutter blade 15. This movable cutter member preferably has the general shape shown in my 80 prior patent, Reissue No. 14420, and is yieldingly held in place in the recess in the temple head by the usual spring 16 coiled at one end about a stud 17 projecting from the side of the bar 4 and at the other end about 85 a stud 18 projecting from the side of the heel 14, this spring acting normally to hold the movable cutter member projected rearwardly with its rearward cutting blade end elevated and with its cutting edge at the 90 rear of the cutting edge of the fixed blade 10. When the heel 14 is struck by the lay the movable cutter member is swung downwardly and projected forwardly to effect a shearing action between the cutting edges 95 of the two blades to sever the filling end extending from the cloth.

In this invention the integral portion of the movable cutter member which is shaped to form the cutter blade 15 is chilled during 100 the operation of the casting of the member and is thus hardened so that it may be ground off to present the required cutting edge 19. This materially simplifies the construction of the movable cutter member over that heretofore employed enabling the entire member to be formed as a single casting cheaply and expeditiously. Thus the expense,

labor and skill required to form a separate steel cutting blade and properly and accurately secure it to the cast body of the movable cutter member is eliminated.

5 In this invention also the effective end of the integral cutter blade 15 of the movable cutter member is formed at a slight angle with respect to the vertical plane of the body 13. When the movable cutter member 10 is in position, therefore, the cutter blade 15 diverges upwardly slightly away from the plane of the stationary cutter as may be observed in Fig. 1. This brings the cutting edge 19 close against the fixed vertical cutter 15 blade 10 and hence if the movable cutter blade be held snugly against the fixed cutter blade an accurate and close coöperation of the two cutting edges is assured when the movable cutter member is carried forwardly 20 by the lay to effect the cutting stroke.

The required pressure of the movable cutting blade against the fixed cutting blade is secured in a simple and effective manner by providing a somewhat resilient metal or 25 steel plate 20 mounted vertically in the recess in the temple head parallel to the fixed cutter blade 10. This plate 20 may be held in position by the set screw 11 already referred to. In order to effect the adjustment 30 of the plate 20, provide for wear, and insure the contact of the plate 20 with the cutter blade 15 a set screw 21 is shown passing through the temple head abutting the plate 20 and held in adjusted position by the lock nut 22. This plate 20 it will thus be observed bears against the cutter blade 15 at the side opposite the stationary cutter blade 10 and at the upper portion of the cutter blade 15 thus giving the required action to 40 insure the effective coöperation of the two cutting edges.

It will thus be seen that a thread cutting temple is provided which is extremely simple and economical in construction and 45 which gives an effective and accurate shearing or severing action.

Having fully described my invention what I claim as new and desire to secure by Letters Patent is:

50 1. A thread cutting temple for looms comprising a vertical stationary cutter member mounted in the temple head, a backwardly and forwardly movable cutter member having a cutter blade diverging upwardly slightly away from the plane of the stationary cutter member, and means for forcing the movable cutter member against the stationary cutter member to bring the cutting edges of the said members into engagement 55 during the cutting stroke.

2. A thread cutting temple for looms comprising a vertical stationary cutter member mounted in the temple head, a backwardly and forwardly movable cutter member having a cutter blade diverging upwardly

slightly away from the plane of the stationary cutter member, and means for engaging the upper portion of said movable cutter blade at the side thereof opposite the stationary cutter member and acting to force the cutting edge of the movable cutter blade into engagement with the edge of the stationary cutter member during the cutting stroke.

3. A thread cutting temple for looms comprising a vertical stationary cutter member 75 mounted in the temple head, a backwardly and forwardly movable cutter member having a cutter blade diverging upwardly slightly away from the plane of the stationary cutter member, a resilient metal plate 80 mounted in the temple head engaging the movable cutter blade at the side opposite the stationary cutter member and acting to force the cutting edge of the movable cutter blade into engagement with the edge of the stationary cutter member during the cutting stroke. 85

4. A thread cutting temple for looms having the construction defined in claim 3 together with an adjustable set screw in the temple head abutting the resilient plate 90 whereby the pressure of the said plate upon the movable cutter blade may be adjusted.

5. In a thread cutting temple for looms a cutter member molded in a single integral piece from cast iron and comprising a body, 95 a heel projecting from one edge of the body, and a chilled cutter blade projecting from another edge of the body with the cutting edge formed on the chilled portion.

6. In a thread cutting temple for looms a 100 cutter member molded in a single integral piece from cast iron and comprising a flat body, a heel projecting from one edge of the body, and a chilled cutter blade projecting from another edge of the body with the cutting edge formed on the chilled portion and with the side surface of the cutter blade containing the cutting edge extending at a slight angle to the sides of the flat body and inclined from the cutting edge toward the 110 center of the flat body.

7. A thread cutting temple for looms comprising a vertical stationary cutter member mounted in the temple head; a backwardly and forwardly movable cutter member molded in a single integral piece from cast iron and comprising a body, and a chilled cutter blade projecting from the rearward edge of the body with the cutting edge formed on the chilled portion; the said cutter blade diverging upwardly slightly away from the plane of the stationary cutter member; and means for forcing the movable cutter member against the stationary cutter member to bring the cutting edges of the said members into engagement during the cutting stroke. 120

In testimony whereof, I have signed my name to this specification.

EDWARD S. STIMPSON,
